TERMINAL HOUSING FOR GASEOUS-
DISCHARGE LAMPSRichard Marone, Corona, N. Y., assignor of one-
half to Anton Feiber, Corona, N. Y.

Application March 17, 1938, Serial No. 196,421

3 Claims. (Cl. 248—50)

The invention relates to terminal housings for gaseous-discharge lamps of the long tube rear-gas type.

Lamps of this type are employed for many purposes and in widely varying conditions of form, dimensions, arrangement and location, and terminal housings now in use are usually made of lacquered sheet metal and are not ordinarily carried in stock but are made to order to meet the special requirements of each particular installation. This entails delay and high costs.

The object of the present invention is to provide a terminal housing having standardized features which enable a relatively small number of designs to meet the requirements of all installations. It will be apparent that a standardized housing may be manufactured in large quantities at low cost, carried in stock, and supplied to customers without delay.

20 Further objects attained by certain features of the invention hereinafter referred to are to improve the safety and efficiency of such housings in use and to facilitate installations and replacements.

25 In the accompanying drawing—

Fig. 1 is a perspective view of a double-socket housing embodying the invention, associated with a pair of lamp tubes.

Fig. 2 is a vertical section of the same.

30 Fig. 3 is a plan view of the same without the tubes.

Fig. 4 is a perspective view of a single-socket housing.

Referring to Figs. 1-3, 1 designates generally 35 the housing block of one embodiment of the invention. It is preferably composed of ceramic or other insulating material and is provided with means for attaching it to a supporting structure, such as the base or flange 2 which is perforated 40 for screws 3. A pair of sockets 4 extend through the housing from top to bottom, being open at the top to receive lamp tubes 5 and at the bottom to allow for lead-in connections.

The web 6 between the sockets has a bore 7 in alinement with holes 8 whereby a connector strip 9 of conductive material may be inserted when it is desired to connect the tubes 5 in series. In this case suitable contacts are provided, for example as shown, springs 10 which 50 provide contact seats for the terminals 11 of the tubes and are secured to strip 9 by means of bolts 12.

In some installations the tubes will not be connected directly with one another but to the 55 power circuit, or rather, to the secondary termi-

nals of a transformer. In this case the strip 9 will be omitted or withdrawn and connection will be made to the leads 13. To protect the supporting structure to which the housing may be attached, sleeves 14 of ceramic or other insulating material are provided, which will be made in lengths sufficient to pass through walls, floors, or other partitions to which the housing may be attached.

As will be seen, the sockets 4 are tapered downwardly and this taper may, as shown in Fig. 2, be increased at the bottom of the sockets to provide supporting seats for the correspondingly tapered upper ends of the sleeves 14. The tapering of the sockets throughout facilitates assembling the sleeves 14, which must be inserted at the top of the housing.

Adjustable means are provided for supporting the fragile tubes in fixed spaced relation to the housing. In the example shown, the supporting 20 means comprises two or more ribs 15 which are preferably integral with the housing and have a vertically undercut cross-sectional shape, such as the almost circular section shown, so that split sleeves 16, or the like, may be telescopically engaged with the ribs with a clamping but slideable fit. In the upper projecting ends of the sleeves 16 are inserted bracket members 17 having channeled seats 18 to receive the lamp tubes and lugs 19 which provide points of anchorage 30 for wires 20 which hold the tubes securely in place.

It will be seen that the tube supports may be telescopically adjusted and this is an important feature because it avoids the necessity of accurately determining in advance the spacing of the tubes from the housing.

The double socket shown in Figs. 1-3, is adapted for use in various types of installations, for example a double tube border for a shop window or the like may be supported by two of the double socket housings. One of the housings in this instance will lack connector strip 9 and will be provided with sleeves 14 as heretofore described, the connection being made to a 40 transformer located below the floor, counter or other support in the rear of the window. The other double socket will be provided with the connector strip 9 (Figs. 2 and 3) and the sleeves 14 will be omitted, the housing in this instance 45 serving as a support and connector for the two tubes. The double socket may also be employed for connecting a plurality of tube sections in 50 single tube series.

The single socket housing shown in Fig. 4 55

is used only where a single-lamp terminal is present. Hence, no provision is made for connector strip 8. Instead, a round hole 24 is provided to receive one end of conductor conduit or pipe 25. A support 26 for the pipe has flanges 27 which are perforated for screws at 28. Ribs 15 are provided on every side of the housing so that the adjustable tube support described with reference to Figs. 1-3 may be made available no matter from which quarter the tube approaches the housing. The single-socket housing will also preferably be open at the bottom so that a sleeve 14 (Figs. 1 and 2) may be inserted when it is desired to connect the tube to the transformer 15 through a floor, wall, or the like.

In some installations it may be necessary or desirable to apply one of the lateral faces of the housing to the supporting structure instead of the base. To meet such conditions the bottom flange 2 may be eliminated and replaced by vertical flanges at two adjacent corners, constituting flush extensions of one of the lateral faces.

It will be apparent that the two types of housing herein described with their accessories, will provide adequate terminal housing facilities for every one of the numerous and various kinds of gaseous-discharge lamp installations.

I claim:

1. A terminal housing for gaseous-discharge lamps comprising a block of insulating material having a socket, and a tube support mounted on said block, said tube support comprising a vertically undercut rib on the exterior of the block parallel to said socket and a spring member telescopically engaging said rib. 5

2. A terminal housing for gaseous-discharge lamps comprising a block of insulating material 10 having a socket, and a tube support mounted on said block and comprising a vertically undercut rib on the exterior of the block parallel to said socket and a split sleeve telescopically engaging said rib. 15

3. A terminal housing for gaseous-discharge lamps comprising a block of insulating material having a socket, and a tube support mounted on said block, said support comprising a vertically under-cut rib on the exterior of said block parallel to said socket, a split sleeve telescopically engaging said rib, and a bracket member having a stem in telescopic engagement with said sleeve and having a seat for a lamp tube. 20
